Des. 632

Wm B. Tilton of New York, N.Y.

Letters Patent No 632 - Dated Feb. 21st 1857

The Schedule referred to in these Letters Patent, and making part of the same

To all whom it may concern:

Be it known that I, William B. Tilton of the City, State, & County of New York have produced a new & original Design for Guitars, & I do hereby declare that the following is a full, clear, & exact description of the same reference being had to the annexed drawing forming part of this Specification, in which,

Figure 1. is a face view of the Guitar - and

Figure 2. is a face view of the plate. -

Similar characters of reference in the several figures, denote the same part of the instrument.

The design, or ornament consists of the plate P, placed within the rosette or opening in the sound board, & slightly below the interior surface of said board: this plate has the form shown in the drawing, & is ornamented by a double row of punctures around the edge of the plate. - This plate hides the interior of the instrument from view, & adds to the ornamental appearance of the guitar.

What I claim as my invention & desire to secure by Letters Patent, is the plate P, placed within the rosette or opening in the sound board, & slightly below the interior surface of said board, said plate hiding the interior of the instrument from view & adding to the ornamental appearance of the guitar, constituting a new & original Design for such instruments.

In testimony whereof I have hereunto signed my name before two subscribing witnesses

T. T. Jones
Robert H. Johnson
